CLAIM

The ornamental design for an orthopedic supporting device, as shown and described.

DESCRIPTION

FIG. 1 is a front perspective view of a design for an orthopedic supporting device at first position;
FIG. 2 is a front view of the design for the orthopedic supporting device as shown in FIG. 1 at first position; rear view being a mirror view;

FIG. 3 is a left side view of the design for the orthopedic supporting device as shown in FIG. 1 at first position;
FIG. 4 is a right side view of the design for the orthopedic supporting device as shown in FIG. 1 at first position;
FIG. 5 is a top view of the design for the orthopedic supporting device as shown in FIG. 1 at first position;
FIG. 6 is a bottom view of the design for the orthopedic supporting device as shown in FIG. 1 at first position;
FIG. 7 is a front perspective view of a design for an orthopedic supporting device as shown in FIG. 1 at second position;

FIG. 8 is a front view of the design for the orthopedic supporting device as shown in FIG. 1 at second position;
FIG. 9 is a right side view of the design for the orthopedic supporting device as shown in FIG. 1 at second position;
FIG. 10 is a top view of the design for the orthopedic supporting device as shown in FIG. 1 at second position;
and,

FIG. 11 is a bottom view of the design for the orthopedic supporting device as shown in FIG. 1 at second position.
The features shown in dashed lines form no part of the claimed design.

1 Claim, 11 Drawing Sheets
